DESIGN FOR A HEALTH LAMP

Leonard P. Young, New York, N. Y.

Application January 7, 1936, Serial No. 60,467

Term of patent 14 years

To all whom it may concern:

Be it known that I, Leonard P. Young, a citizen of the United States and resident of New York, in the county of Queens and State of New York, have invented a new, original, and ornamental Design for a Health Lamp, of which the following is a specification, reference being had to the accompanying drawing, forming part thereof, in which

Figure 1 is a front elevation of the health lamp

showing my new design, in which the ornamental interior of the lamp is perceptible; and

Figure 2 is a side elevation thereof.

I claim:

The ornamental design for a health lamp as shown and described.

Dated, New York, N. Y., this 6th day of January, 1936.

LEONARD P. YOUNG,
